UNITED STATES PATENT OFFICE.

WILLIAM H. WOOD, OF CLEVELAND, OHIO.

LAMP.

1,235,275.

Specification of Letters Patent. Patented July 31, 1917.

Application filed May 5, 1916. Serial No. 95,542.

To all whom it may concern:

Be it known that I, WILLIAM H. Wood, a citizen of the United States, residing at Cleveland, in the county of Cuyahoga and 5 State of Ohio, have invented a certain new and useful Improvement in Lamps, of which the following is a full, clear, and exact description, reference being had to the accompanying drawings.

10 This invention relates to lamps and more particularly to the lamps which are employed on motor vehicles. Safety and convenience of vehicle operation in the dark requires a strong and uniform illumination of 15 the ground for a considerable distance in front of the machine, yet also requires keeping the rays of light sufficiently low to avoid blinding the eyes of men and animals moving in the opposite direction. Most expedi- 20 ents heretofore adopted satisfy the second requirement by sacrificing the first requirement in some way, either by so changing the focus of the light rays as largely to neutralize their forward projection, or by employ- 25 ing an obscure coating over the face of the lamp. The object of the present invention is the provision of a reflector of such nature as to secure a true scientific projection of the light in the distribution desired, for a 30 great distance in front of the automobile and in a uniform manner as regards the ground, while directing all the rays downwardly so as to avoid the blinding heretofore mentioned; the provision with a single light 35 source of a plurality of main reflecting systems and intermediate systems interposed between the main systems to form a transition from one to the other; the provision of a reflector system in which a maximum of 40 efficiency of light projection and distribution shall be secured; while further objects and advantages of the invention will become apparent as the description proceeds.

In the drawings accompanying and forming 45 a part of this application I have illustrated certain lamp reflectors constructed in accordance with my invention, together with certain diagrammatic views illustrating the scientific theory of the same. In these drawings, Figure 1 is a perspective view of a reflector constructed in accordance with my invention, a lamp bulb being illustrated in dotted lines therein; Fig. 2 is a vertical sectional view through the center of the reflector shown in Fig. 1 and drawn to larger scale; Fig. 3 represents a front elevation of

the said reflector; Fig. 4 is a perspective view of a modified form of reflector constructed in accordance with my invention; Fig. 5 is a vertical sectional view through the center of the reflector shown in Fig. 4; Fig. 6 is a diagrammatic view showing the mode of reflection of light rays derived from sources located at different positions along the axis of a parabolic reflector; Fig. 7 is a 65 diagrammatic view illustrating the mode of reflection of light rays derived from a source displaced from the axis of a parabolic reflector; Fig. 8 is a diagrammatic view showing one half of a parabolic reflector with 70 the light source arranged upon its axis and slightly forward of the focus; Fig. 9 is a view of the opposite half of a parabolic reflector slightly inclined to the horizontal and having its light source above the axis; Fig. 75 10 illustrates a combination of the two reflectors indicated in Figs. 8 and 9 about a single source; and Fig. 11 illustrates one use of my improved lamp.

Describing the drawings by characters of 80 reference, attention being first given to Fig. 6, A represents a parabolic reflecting surface having an axis $a-a$ and a focus F. According to the well known principles of optics, all light rays emanating from a 85 source placed exactly at this focus will be reflected forwardly in strictly parallel lines as shown by the full lines in Fig. 6; all light rays emanating from a source located on the axis outside of the focal point, as at S^1 will 90 be converged as shown by the dotted lines in Fig. 6, though not toward any single point; and all light rays emanating from a light source located along the parabolic axis inside of the focal point will be diverged 95 after reflection as indicated by the dot-and-dash lines in Fig. 6.

Referring next to Fig. 7 wherein A represents the same parabolic reflector, $a-a$ its major axis and F its focal point, if the 100 light source be moved to one side of the axis as to the point S^3 , all rays emanating therefrom will be thrown toward the opposite side of the axis $a-a$. Thus if the line $a-a$ considered as horizontal and the source S^3 105 elevated above that axis the reflected rays will have a downward tendency, which tendency will be present regardless as to whether the source be located at the point S^3 which is substantially upon the parameter or be located outside or inside of the same as indicated at S^4 , S^5 respectively, al- 110

though the dispersion or convergence of the light rays will be modified slightly.

- Therefore if a half parabola be taken as shown at B in Fig. 8, and a light source S be placed upon its axis $b-b$ but at a point outside of its focus there will be a tendency for the light to be thrown outward and slightly converged; and if a second complementary half of a similar parabola as C in Fig. 9 be located with its axis $c-c$ inclined to the horizontal H-H and be provided with light from a source S placed above its axis and within its focal point, the light rays reflected thereby will have a downward tendency for three reasons; the inclination of the reflecting surface, the location of the source above the axis, and the location of the source at the rear of the focal point.
- Hence it is entirely feasible to combine these two half parabolas into a single whole as shown in Fig. 10, since the inclination of the axes will cause a light source S which is exactly upon the axis $b-b$ of the upper surface to fall above the axis $c-c$ of the lower surface; and while it is necessary to the best results to locate the source forward of the focal point of the upper parabola and rearwardly of the focal point of the lower parabola, this can easily be effected by making the lower parabola of slightly larger size so that its focal point will naturally fall ahead of the focus of the upper surface, and if the light source be then located at any point between these two foci, every condition hereinbefore pointed out will be completely attained.

However the preceding explanation applies only to the upper and lower portions of the reflecting surfaces, and ignores their horizontal or intermediate portions corresponding generally to the region included between the lines $b-b$ and $c-c$ of Fig. 10. If it be attempted merely to merge one surface into the other at this point, it will be found that the reflection of the light according to these two systems will produce an uncertain and confused reflection. Therefore according to my invention I connect these two parabolic surfaces by a surface which in cross section is everywhere inclined from below inwardly as shown in Figs. 3 and 4, the result being that the light rays striking this part of the reflector are also thrown downwardly where they will aid the operation of the vehicle and avoid any blinding effect.

In Figs. 1 to 5 inclusive, I have illustrated some actual reflectors containing these improvements. In Figs. 1, 2 and 3, 1 represents a segment of a parabolic surface corresponding to the portion B in Fig. 10, and 2 a section of a second parabolic surface corresponding to the portion C in Fig. 10. Each of these parabolic surfaces

is terminated before it reaches the horizontal, the upper reflector at the line 3-3, and the lower reflector along the line 4-4 angularly related therewith. The angular space defined between these lines is occupied by a reflector portion 5, which naturally inclines inwardly from the fact that the parabola 2 is larger than the parabola 1 so that the desired direction of reflection is secured. However it should be understood that these views are very greatly exaggerated for purposes of clearness, and that in practice the benefits of my invention will be secured with inclinations and divergences very much less than those here shown.

The light source will ordinarily consist of incandescent light bulbs illustrated at 6, and here shown as secured in a socket carried by a hollow boss 7 in the axis of the reflector, although it is obvious that this hollow boss could be projected through other portions of the wall if desired. In Fig. 2, α represents the focal point of the surface 1 and b that of the surface 2. Owing to the fact that the source of light produced by an incandescent lamp bulb is not a geometrical point, but is a region of appreciable size, notwithstanding the compactness of construction in lamps provided for this use, the exact theoretical requirements of the preceding demonstration cannot be secured, but all practical features thereof are obtained when the lamp bulb is so arranged that the rearward or inward portion of its filament traverses substantially the point α while the outermost portion is above and preferably inside the point b , which condition can easily be obtained.

In Figs. 4 and 5 I have illustrated a modification of my said invention wherein the upper parabolic surface 10 and the lower parabolic surface 11 are of the same size, the axis of the lower being inclined from the horizontal as before. In order to provide the inclined lateral portions of the reflector which are characteristic of my invention, I flare slightly outwardly the uppermost portions of the lower parabola as shown at 12-12, and I draw slightly inwardly the lowermost portions of the upper parabola as shown at 13-13, thus providing for the inclined portions 14-14.

It will be understood that the illustration in Figs. 4 and 5 is much exaggerated for purposes of clearness. With this arrangement the focal points of the two surfaces are arranged as shown in Fig. 5, α representing the focus of the upper surface and d that of the lower surface. The lamp 15 is located so that its filament falls just forward of the focus c and above, though also slightly forward of the focus d . In this case the rays striking the upper parabola will be thrown downwardly by the converg-

ing action and thus striking the lower parabola will be thrown downwardly by reason of the inclination of that parabola and by reason of the location of the source above its axis.

- 5 In Fig. 11 I have illustrated the effect of employing my improvements upon an automobile, wherein 20 indicates one of the front wheels and 21 one of the forward lamps.
- 10 The converging effect of the upper half of the reflector throws the rays 22 downwardly but to a considerable distance in front of the machine; the diverging effect of the lower half of the reflector sends the rays 23 also downwardly beneath the first rays, while also spreading them over the road surface; the side portions of the reflectors direct the rays even more sharply downward as shown at 24, covering the road near and at 20 the sides of the machine. It will be understood that the angles are shown as excessively sharp in this drawing because of limitation of space.

While I have described my invention in detail it will be apparent that numerous variations may be made in such details and in the application of those details to various lamps, wherefore I do not restrict myself except as required by the claims hereto annexed or the prior state of the art.

Having thus described my invention, what I claim is:

1. The combination with a vehicle of a lamp having a reflector whose upper part is of parabolic shape with its axis substantially horizontal and whose lower part is of parabolic shape with its axis inclined downwardly, said lamp having a light source located substantially on the axis of such upper surface and above the axis of such lower surface and forward of the focal point of such upper surface.

2. The combination with a vehicle of a lamp having a light source and a reflector whose upper part is adapted to converge the light from said source, whose lower part is adapted to disperse the light from said source, and whose lateral portions are adapted to throw downwardly the light from said source.

3. The combination with a vehicle of a lamp having a reflector whose upper part is of parabolic shape with its axis substantially horizontal and whose lower part is of parabolic shape with its axis inclined downwardly and whose lateral parts are independent of both parabolic portions and inclined inwardly, said lamp having a light source above the axis of the lower parabola and forward of the focal point of the upper parabola and near the axis of said upper parabola.

4. A lamp reflector having its upper and lower parts formed as separate surfaces of revolution arranged substantially about a

common axis, and having its intermediate parts formed separately from both surfaces of revolution and inclined toward each other at one side.

5. In a lamp, a light source, and a reflector having one of its sides of parabolic shape with its focal point inside said source and its opposite side of parabolic shape with its focal point outside said source, the axes of said parabolic portions being angularly related.

6. In a lamp, a light source, and a reflector having one of its sides of parabolic shape with its focal point inside said source and its opposite side of parabolic shape with its focal point outside said source and with its intermediate portion separate from both said parabolic surfaces and arranged to throw the light toward the side of said second surface.

7. A lamp reflector having a pair of opposed semi-parabolic reflecting surfaces whose adjacent edges are connected by inclined portions whose cross sections upon planes transverse to the parabolic axis are substantially straight.

8. A reflector having a pair of opposed semi-parabolic reflecting surfaces arranged in flaring relation to each other, the adjacent marginal portions of said parabolic surfaces being connected by a reflecting surface distinct from each of them.

9. In a lamp, a reflector having a pair of opposed semi-parabolic reflecting surfaces arranged in flaring relation to each other, the adjacent marginal portions of said surfaces being connected by non-paraboloidal reflecting surfaces, and a light source located substantially at the axis of one surface and at one side of the axis of the other surface.

10. In a lamp, a reflector having a pair of opposed semi-parabolic reflecting surfaces arranged in flaring relation to each other, a light source located substantially at the axis of one surface and at one side of the axis of the other surface, and intermediate reflecting surfaces one at each side of the lamp and connecting the adjacent margins of the parabolic surfaces, said intermediate surfaces being arranged to reflect the light falling thereon in a direction past the axis which is the farther from said light source.

11. A reflector having a pair of opposed semi-parabolic surfaces, one being of larger diameter than the other and the two surfaces being continuous at their vertices whereby their focal points are separated.

12. In a lamp, a reflector having a pair of opposed semi-parabolic surfaces, one being of larger diameter than the other and the two surfaces being continuous at their vertices whereby their focal points are separated, and a light source located between said focal points.

13. A reflector having a pair of opposed

- semi-parabolic surfaces, one being of larger diameter than the other, the two surfaces having a substantially common vertex and having their axes diverging from that point.
- 5 14. In a lamp, a reflector having a pair of opposed semi-parabolic surfaces, one being of larger diameter than the other, the two surfaces having a substantially common vertex and having their axes diverging from that point, and a light source located substantially upon the axis of the smaller parabolic surface between the focal points of the two parabolic surfaces.
- 10 15. A reflector having a pair of opposed semi-parabolic surfaces, one being of larger diameter than the other and the two surfaces being substantially continuous at their vertices, the adjacent marginal edges of the parabolic sections being joined by a reflecting surface which is separate from each of them and is inclined at every point toward the smaller parabolic surface.
- 15 16. In a lamp, a reflector having a pair of opposed semi-parabolic surfaces located upon opposite sides of a single light source, said surfaces substantially meeting each other at points near the foci and diverging gradually with increasing distances from said foci, and a reflecting surface bridging the gap and arranged to reflect the rays from said source toward one of said parabolae.
- 20 17. In a headlight, the combination of a pair of opposed semi-paraboloid reflecting surfaces having their axes angularly disposed, the axis of the upper portion being substantially horizontal and that of the lower portion inclined downwardly and forwardly, and a light source located on the axis of the upper and above the axis of the lower.
- 25 18. The combination with a semi-paraboloid reflecting surface, of a second generally semi-paraboloid reflecting surface opposed thereto, the foci of the two surfaces being spaced at different longitudinal points and their axes being divergent.
- 30 19. The combination of a reflecting member, comprising a pair of approximately semi-parabolic surfaces opposed to each other, and one or more surfaces additional thereto and interposed between them.
- 35 20. In a lamp a reflector comprising upper and lower parabolic sections, a source of light located substantially upon the axis of the upper section, there being on each side of the source of light and between the sections a reflecting surface arranged to reflect rays from said source downwardly and forwardly through the open front of said reflector.
- 40 21. In a reflector a pair of opposed paraboloid sections of which one at least subtends less than 180° , whereby a gap is formed between their adjacent margins, and independent reflecting surfaces interposed in said gap and arranged to reflect the rays falling thereon forwardly through the open front of said reflector and to one side of its axis.
- 45 22. In a headlight, a reflector having a pair of opposed paraboloid sections arranged with their axes diverging, neither subtending an angle greater than 180° , whereby a gap is formed between their adjacent margins, and independent reflecting surfaces located in said gap and arranged to reflect the rays falling thereon downwardly and forwardly through the open front of said reflector.
- 50 23. A headlight for automobiles comprising, in combination, a reflector having a pair of opposed semi-paraboloid surfaces arranged one above the other, the axis of one at least being substantially horizontal and subtending less than 180° , and a light source on the axis of said surface.
- 55 24. In a headlight, a reflector having a semi-paraboloid surface supported with its axis substantially horizontal, and a light source arranged to project an approximately horizontal beam, said surface subtending less than 180° , and the remainder of said reflector consisting of reflecting surfaces arranged to throw downwardly of said first beam.
- 60 25. A headlight for automobiles comprising, in combination, a reflector having a semi-paraboloid portion arranged with its axis substantially horizontal, and a light source associated therewith for distant lighting, said portion being symmetrical with respect to a vertical plane and subtending less than 180° whereby no part of the light reflected by that portion will be thrown laterally in a horizontal plane.
- 65 26. A reflector having different parts of different sized paraboloids, all having a common vertex.
- 70 27. In a headlight, a one-piece reflector containing independent paraboloid surfaces having a common vertex and spaced focal points, and a light source located between said focal points.
- 75 28. In a lamp, a reflector made in one piece having opposed paraboloid surfaces whose margins are spaced apart, and a simple curved surface connecting said margins and having its normals falling upon one side of the lamp axis.
- 80 29. In a lamp, a reflector having a pair of opposed parabolic reflecting portions arranged with their axes in angular relations and united by flat faces at each side thereof.
- 85 30. In a headlight, a reflector made in one piece and having a pair of opposed semi-paraboloid surfaces disposed below and above a substantially horizontal line, the adjacent margins of said surfaces being connected by integral bridges which provide

additional reflecting faces between the paraboloid surfaces.

31. In a lamp, a light source, and a reflector having one of its sides of parabolic shape with its focal point inside said source and its opposite side of parabolic shape with its focal point outside said source, the opposite sides of said reflector being continuous through a common vertex.

10 32. In a lamp, a reflector having its opposite sides of parabolic shape but of unequal parameter, and having a common vertex whereby the focal point of one portion lies nearer said common vertex than the focal point of the opposite portion, and a light source located at a distance from said common vertex intermediate the distances of said two focal points.

15 33. In an automobile headlight, the combination of a pair of opposed semi-parabo-

loid reflecting surfaces located one above the other and having their axes flaringly disposed, and a light source located on the axis of the upper surface and above the axis of the other surface.

25

34. A lamp reflector having its upper and lower parts formed as the surfaces of revolution of different generators, said surfaces being arranged substantially about a common axis.

30

35. A reflector for automobile lamps having its upper and lower portions of unequal size of semi-paraboloid form, the upper portion having its axis horizontal and the lower portion having its axis inclined downwardly at a small angle.

35

In testimony whereof, I hereunto affix my signature.

WILLIAM H. WOOD.

DISCLAIMER.
